CONICAL CRUSHING MILL.

Application filed February 5, 1927, Serial No. 166,229, and in Germany August 6, 1925.

The present invention relates to crushing elements for conical crushing mills.

It is known in conical crushing machines to make the crushing cone, fastened on the shaft, of two concentric portions namely, a seating element rigidly keyed on to the shaft and having cylindrical seating surfaces graduated outwardly in steps, and a single integral crushing mantle stepped internally 10 corresponding to the fixed element, and to connect these two parts by means of wedges or keys. It is also known to provide the seating element externally with a surface in the form of a truncated cone tapering 15 towards the top, and to fasten the crushing mantle, correspondingly shaped internally, on the seating element, which it surrounds with free play, by casting into the free space hard lead (lead-antimony alloy) or the like. 20 Considerable difficulties occur however, in these known constructions of the crushing cone in obtaining a permanently secure connection during the action between the seating element and the crushing mantle fastened thereon, as the particularly high crushing pressure set up at the lower end of the crushing cone where the greatest disintegration of the material occurs, causes a very great tendency to a loosening in a 25 radial direction. This loosening leads, when the machine is held in action to damage of the crushing cone and the seating element, and also lowers the efficiency of the crushing machine, so that parts must be renewed 30 prematurely.

The invention relates to a crushing cone the mantle of which is mounted on a stepped seating element or a stepped axle, if no seating element is used, and in which the 40 connection between the mantle and the seating element or the shaft is secured by a special construction of the seating surface.

The arrangement according to the present invention is characterized by the feature that 45 all or some steps or at the least the lowest step of the seating element or the shaft are under-cut, the upper edges of the under-cut steps however only projecting so far that the crushing mantle can be placed in position 50 and is prevented from being stripped off

after the intermediate space between the mantle and the seating element has been filled up by the filling mass such as hard lead. Preferably the lowest steps only are under-cut.

The under-cutting of the portions of the steps is preferably effected by giving them a conical shape the cone of which runs in the opposite direction to the external cone of the crushing mantle.

If a crushing cone constructed according to the invention becomes loosened by stresses set up during operation, a small axial displacement of the crushing mantle in upward direction is sufficient to fix it again onto the 65 under-cut seating surfaces.

This small axial displacement of the crushing mantle may be effected by an adjusting mechanism of suitable type, for example by screws.

Setting screws in cylindrically bored crushing cones are known which put the latter against a fixed flange and interchangeable intermediate elements, and render possible an adjustment of the crushing cone in 75 a vertical direction. Loosening of the crushing cone on its seating face in a radial direction cannot however be avoided by this means.

One form of construction of the improvement is shown in the drawings:

Figure 1 is a partial elevation of a conical crushing machine in vertical section along the dotted line C—D in Figure 2.

Figure 2 is a section of the crushing cone 85 in the direction A—B, the outer parts of the crushing machine being omitted.

The stepped seating element 2 is fastened on the shaft 1 by means of keys 9, and is enclosed by the crushing mantle 3 with a certain amount of free space, the intermediate free space 4 left being filled up with cast hard lead such as lead-antimony alloy.

A number of grooves 5 preferably four in number, in one of which engages the projection 6 of the crushing mantle 3 in order to prevent the same rotating on the seating element 2, are provided in the latter.

In the shown form of construction only the two lower steps 8 of the seating element 100

2 are under-cut. This construction has particular advantages. The greatest strain on the crushing mantle occurs at its lowest part. Consequently essentially in this part of the 5 mantle an expanding or spreading of the material and thus a loosening between mantle and seating element occurs. If therefore, the upper steps of the seating are cylindrically shaped as shown in the example illustrated, an axial displacement of the crushing 10 mantle 3 on the seating element 2 in order to overcome the loosening in the lower parts of the mantle is possible, if the upper parts of the mantle are not expanded owing 15 to the slighter strains executed thereon by the crushed material.

A similar effect is obtained if only the lowest step of the seating element is under-cut.

The angle of under-cut relative to the 20 axis of the seating element is sufficiently small whereby the upper edges of the under-cut steps project only so far that the crushing mantle placed in position as a single unitary element is prevented from being 25 stripped off by the cooperation of the under-cut steps and the mass of filling material.

Adjusting screws 7 are arranged on the lower end of the seating element 2 which press on the crushing mantle 3 from below 30 and force it firmly against the under-cut step faces of the seating element.

The undercut lower steps and also the remaining cylindrical steps may be provided directly on the shaft itself by suitably 35 strengthening the same. The special seating element is then dispensed with.

We declare that what we claim is:

1. A conical crushing mill including a 40 conical crushing mantle, a shaft and a seating element fixed to the shaft, a mass of hard lead or the like material filling up the intermediate space between the crushing mantle and the seating element, steps on the seating element, one or more of the steps of the seating element being under-cut.

2. A conical crushing mill including a 45 conical crushing mantle, a shaft and a seating element fixed to the shaft, a mass of hard lead or the like material filling up the intermediate space between the crushing mantle and the seating element, steps on the seating element, one or more of the steps of the seating element being under-cut so that these have a conical shape oppositely inclined to 55 the outer cone of the crushing mantle.

3. A conical crushing mill including a 60 conical crushing mantle, a shaft and a seating element fixed to the shaft, a mass of hard lead or the like material filling up the intermediate space between the crushing mantle and the seating element, steps on the seating element, only the lowest step or steps of the seating element being under-cut.

4. A conical crushing mill including a 65 conical crushing mantle, a shaft and a seat-

ing element fixed to the shaft, a mass of hard lead or the like material filling up the intermediate space between the crushing mantle and the seating element, steps on the seating element, one or more of the steps of the seating element being under-cut, whereby the angle of undercut is so small that whilst a locking effect is obtained by a relatively small axial displacement of the crushing mantle against the stepped seating element 70 stripping the mantle onto the seating element from the top of the same is possible.

5. A conical crushing mill including a stepped seating element and a shaft forming a unitary body therewith, a crushing mantle 80 surrounding said stepped seating element, a mass of hard lead or the like substance filling up the space between the stepped seating element and the crushing mantle, under-cut surfaces on the stepped seating element and 85 adjusting devices provided on the seating element or on the shaft, by which the crushing mantle when loosened is brought again into a position where it is firmly fastened by transmission of the filling mass to the 90 under-cut steps.

6. A conical crushing mill including a stepped seating element and a shaft forming a unitary structure therewith, a crushing mantle surrounding said stepped seating 95 element, a mass of hard lead or the like substance filling up the space between the stepped seating element and the crushing mantle, under-cut surfaces on the stepped seating element, set-screws arranged in the 100 lower end of the seating element or below the mantle on the shaft and pressing on the crushing mantle from below, by which the crushing mantle when loosened, is brought back into a position where it is firmly fastened by transmission of the filling mass to 105 the under-cut steps.

7. A conical crushing mill including a shaft, a stepped seating element rigidly mounted on the shaft by key or the like 110 means, a crushing mantle, a mass of lead or the like material adapted to fill up the space between the stepped seating element and the crushing mantle, the steps on the seating element being under-cut to form a conical 115 shape running in the opposite direction to the outer conical shape of the crushing mantle.

8. A conical crushing mill including a shaft, a stepped seating element fixed to the 120 shaft, a crushing mantle surrounding said seating element, a mass of material such as lead for filling up the intermediate space between the crushing mantle and the seating element, under-cut steps on the seating element, means for displacing axially the crushing mantle against the seating element to provide rigid locking between this and the crushing mantle.

9. A conical crushing mill including a 130

shaft, a seating element shaped of one body with the shaft, a crushing mantle surrounding said seating element, a mass of material such as lead for filling up the intermediate space between the crushing mantle and the seating element, under-cut steps on the seating element, means for displacing axially the crushing mantle against the seating element

to provide rigid locking between this and the crushing mantle. ¹⁰

In witness whereof, we have hereunto signed our names this 18th day of January, 1927.
